(57) CLAIM

The ornamental design for a baby carrier with hood, as shown and described.

DESCRIPTION

The patent or application file contains at least one drawing executed in color. Copies of this patent or patent application publication with color drawing(s) will be provided by the Office upon request and payment of the necessary fee.

FIG. 1 is a rear elevation view of a baby carrier with hood embodying our new design.

FIG. 2 is a rear elevation view thereof with the hood in a second position.

FIG. 3 is rear elevation view thereof with the hood in a third position.

FIG. 4 is a front elevation view thereof with the hood in the third position.

FIG. 5 is a front elevation view thereof with the hood in the first position; and,

FIG. 6 is a front elevation view thereof with the hood in the second position.

The “je porte mon bebe” logo appearing in FIGS. 1-3 is a registered trademark owned by Applicant (i.e., JE PORTE MON BEBE of La Garde, France).
